UNITED STATES PATENT OFFICE.

DORMAN SCHAEFFER, OF HELENA, MONTANA.

RIDING TOY.

Application filed July 2, 1926. Serial No. 120,147.

This invention relates to a wheeled toy which is propelled by the feet of a child sitting on the toy pushing against the pavement, the general object of the invention being to provide an attractive, durable and inexpensive toy which will resemble somewhat an airplane.

Another object of the invention is to provide means for limiting the turning movement of the front axle so as to prevent the toy from turning over, due to the axles being turned too much.

This invention also consists in certain other features of construction and in the combination and arrangement of the several parts, to be hereinafter fully described, illustrated in the accompanying drawings and specifically pointed out in the appended claims.

20 In describing my invention in detail, reference will be had to the accompanying drawings wherein like characters denote like or corresponding parts throughout the several views, and in which:

25 Figure 1 is a plan view of the device.

Figure 2 is a longitudinal sectional view.

Figure 3 is a section on line 3—3 of Figure 2.

30 Figure 4 is a section on line 4—4 of Figure 2.

In these views, 1 indicates the body of the device which is preferably formed of a solid piece of wood which has but little horizontal width and which is of considerable length, 35 with its lower edge straight and its upper edge tapering from the front end to the rear end. An intermediate portion of the upper edge is cut away to provide a horizontal part 2 to which is fastened the seat 3 so that 40 said seat is flat. The seat is also of but little width so that it will not interfere with the use of the legs of the child when the occupant of the seat straddles the body and uses his legs for propelling the device along a 45 surface. The narrow form of the body also facilitates the use of the legs in the propelling action. A pair of depending pieces 4 is fastened one on each side of the tail end of the body by the screws 5, for instance, and these pieces support the shaft 6 of the 50 rear wheel 7.

The front wheels 8 are carried by the spindles 9 which enter holes formed in the front axle 10, this axle having an upwardly extending central part 10' which is provided with a socket 11 to receive the lower end of

the steering post 12 which passes through a vertical hole 13 formed in the front part of the body. A screw 14 passes through the upper part of the extension 10' and through 60 the steering post, thereby fastening the post to the axle. A washer 15 is arranged between the body and the part 10' to prevent wear.

The upper end of the post is provided with 65 a handle 16 so that it can be turned by the occupant of the seat 3 and the screw 14 is provided with an extension 14' which passes through a yoke member 16' which is fastened to the body and depends therefrom, this arrangement of parts limiting the turning 70 movement of the front axle and thereby preventing upsetting of the device through the turning of the axle too far.

A narrow board 17 is passed through an 75 inclinedly arranged slot 18 made in the front part of the body, this board projecting well beyond each side of the body and forming a wing. The steering post 12 passes through this wing and a screw 19 may be used to hold it in place. A tail forming board 20 is fastened to the tail end of the body, and this board forms an extra seat which may be used by a passenger or it may be used by a 80 single occupant in coasting.

85 As will be seen, the steering post 12 is vertically arranged and the bearing surfaces between the part 10' and the body lie in a horizontal plane so that the device is less likely 90 to tip over when being turned, as it would if these parts were arranged otherwise.

95 As will be seen, the device is very durable and can be manufactured to sell at low cost and will be extremely attractive to a child on account of its resemblance to an airplane and to the ease with which the child can propel and steer it. The means for limiting movement of the front axle also eliminates danger of the device upsetting.

100 It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

110 1. A device of the class described comprising a body, wheels connected with the rear end of the body, a seat fastened to the upper edge of the body, a front axle, a

- wheel carried thereby, a steering post rotatably supported by the body and held against other movements, means for connecting the post to the axle and interengaging members connected with the body and post for limiting the turning movement of the post and axle.
2. A device of the class described comprising a body tapering from the front to the rear, a seat fastened to the upper edge of the body, said seat lying in a horizontal plane, an axle carrying depending part at the rear of the body, a wheel on said axle, a front axle, wheels carried thereby, a steering post passing through the front part of the body, means for connecting the post to the axle, means for limiting the turning movement of the
- 5
- 10
- 15

post and axle, such means comprising a depending yoke on the body and a projection on the axle engaging the yoke.

3. A device of the class described comprising a narrow elongated body having a slot in its front portion which slopes downwardly toward the rear, a wing forming member passing through the slot, a combined seat and tail piece connected with the tail end of the body, a horizontally arranged seat fastened to the body intermediate its ends, a rear wheel carried by the body, a front axle, wheels carried thereby, and a steering post passing through the body and ring and connected with the front axle.

In testimony whereof I affix my signature.

DORMAN SCHAEFFER.
